(57) **CLAIM**

The ornamental design for a roof sensor with antennae, substantially as shown and described.

DESCRIPTION

FIG. 1 is a perspective view of an embodiment of a roof sensor with antennae showing our design.

FIG. 2 is a front view thereof.

FIG. 3 is a back view thereof.

FIG. 4 is a left side view thereof.

FIG. 5 is a right side view thereof.

FIG. 6 is a top view thereof.

FIG. 7 is a bottom view thereof.

FIG. 8 is a perspective view of an alternate embodiment of a roof sensor without an antennae showing our design.

FIG. 9 is a front view thereof.

FIG. 10 is a back view thereof.

FIG. 11 is a left side view thereof.

FIG. 12 is a right side view thereof.

FIG. 13 is a top view thereof; and,

FIG. 14 is a bottom view thereof.

Elements identified in broken lines in the accompanying drawings form no part of the claimed invention.
